DESIGN FOR A NEGLIGEE

Ilsa Herdegen, New York, N. Y.

Application September 28, 1939, Serial No. 87,406

Term of patent 3½ years

To all whom it may concern:

Be it known that I, Ilsa Herdegen, a citizen of the United States of America, residing in New York city, in the Borough of Manhattan, county and State of New York, have invented a new, original and ornamental Design for a Negligeé, of which the following is a specification, reference being had to the accompanying drawing, forming part thereof, wherein

I claim:

The ornamental design for a negligeé, substantially as shown,

ILSA HERDEGEN,
